TOY TRAIN

Frederick J. Pfersdorf, 37 N. Woodland Trail,
Palos Park, Ill. 60464

Filed Feb. 23, 1966, Ser. No. 1,151

Term of patent 3½ years

(Cl. D34—15)

FIG. 1 is a side elevational view of a toy train showing my new design, the side opposite being substantially similar as that shown;

FIG. 2 is a bottom plan view thereof;

FIG. 3 is a top plan view thereof;

FIG. 4 is a front elevational view thereof taken along lines 4—4 in FIG. 1; and

FIG. 5 is a rear elevational view thereof taken along lines 5—5 in FIG. 1.

The broken line showing of tracks are for illustrative purposes only.

I claim:

The ornamental design for a toy train, substantially as shown and described.
